UNITED STATES PATENT OFFICE.

PATRICK DEGNAN AND MICHAEL MEYER, OF ST. LOUIS, MISSOURI.

HORSE-COLLAR.

SPECIFICATION forming part of Letters Patent No. 308,881, dated December 9, 1884.

Application filed June 21, 1884. (No model.)

To all whom it may concern:

Be it known that we, PATRICK DEGNAN and MICHAEL MEYER, citizens of the United States, residing at St. Louis, in the State of Missouri, have invented a new and useful Improved Horse-Collar, of which the following is a specification.

Our essential objects are to make the throat or under portion of horse-collars to be elastic, yielding, and self-adapting to the movements of the animal, especially avoiding all choking or injurious strain upon the throat or chest of the animal, and otherwise render the collar (by its cushion and throat parts) better adapted to fit, accommodate, and be more comforting to the animal. We attain these objects by the mechanism illustrated in the accompanying drawings, in which—

Figure 1 is an elevation of our improved horse-collar, with parts broken away to better show the construction inside of the "throat" portion. Fig. 2 is a bottom plan of the collar. Fig. 3 is a cross-section taken on line 3 3.

Similar letters refer to similar parts throughout the several views.

A A' are the side pads or shoulder-cushions of the collar. These cushions do not extend completely round the under or throat portion of the collar, but only from the neck a to the throat portions, marked b b'. (See Figs. 1, 2.) The neck-roll A² forms part of the collar, in manner usual, as shown.

From the points b b' the under, or what we term the "throat," portion B we have improved as follows: We make the continuity from the lowest extremity of the one cushion, b, to the like point of the opposite cushion, at b', to consist of a tubular leather throat, B, (see figures;) secondly, we insert in this throat B a solid cylindrical-shaped piece of rubber or its equivalent, so that it is the combination of this rubber b², (as a stuffing or filling,) together with the tubular leather throat B, that constitutes the elastic or yielding throat

portion of the collar. The rubber b² gives 45 elasticity or flexibility, and always tends to return to its proper shape and preserve the contour of the collar. This rubber is hidden within the leather throat B, its ends being pointed and riveted to the leather. (See Fig. 50 1.) Conjointly the outside leather throat B and inside cylindrical piece of rubber b² form a solid as well as uniform cylindrical throat portion from the points b to b'. The neck-roll 55 is united to the side cushions, A A', the latter having the leather tubular throat B, provided with the rubber inside properly fastened at its ends; finally, all is stuffed in manner ordinary, the straw reaching completely to the ends where the rubber is fastened. (See Figs. 1, 2.) 60

Our invention adapts the under or throat portion, B, of the collar to better accommodate the movements of the animal. It also adapts the collar to better fit and yield to the chest of the animal and otherwise overcomes the disadvantages arising from a collar having a rigid throat portion.

We are aware that horse-collars have been made with a rim or "neck-roll" provided with a piece of india-rubber, or of rubber and straw, but such we do not claim.

What we claim is—

1. In a horse-collar, the pads or cushions thereof, having their lower ends connected together by a tubular leather throat portion, 75 B, containing the rubber filling b², substantially as and for the purposes set forth.

2. In a horse-collar, the combination of the pads or cushions having their lower ends connected together by a tubular leather throat, B, 80 so the rubber filling b² inside of same, and the neck-roll A², all constructed to operate substantially as and for the purposes set forth.

PATRICK DEGNAN.
MICHAEL MEYER.
